UNITED STATES PATENT OFFICE.

SOLOMON M. MILLER, OF CHICAGO, ILLINOIS.

PUMP FOR REFRIGERATING SYSTEMS.

Application filed July 8, 1921. Serial No. 483,147.

To all whom it may concern:

Be it known that I, SOLOMON M. MILLER, a citizen of the United States, residing at Chicago, in the county of Cook and State of Illinois, have invented a new and useful Improvement in a Pump for Refrigerating Systems, of which the following is a specification.

My invention relates to refrigerating systems, and more particularly to the means for pumping, compressing and propelling or imparting motion to the refrigerating fluid carried through the system. One of the primary objects of my invention is the provision of an apparatus that is constructed in a manner so that the refrigerating fluid as it passes through the pump or pressure generator will not become mixed with, or interfered with, by the lubricating material, such as oil or the like. Further objects of my invention are the provision of a pump that is compact in construction; is novel in its principles and effective in performing the functions for which it has been designed. Further objects will be apparent to others after an understanding of my invention is had.

Referring to the drawings that form a part of this specification, Figure 1 is a schematic view of a refrigerating system showing the arrangement of the divers elements, including my improved generator or pump.

Figure 2 is a longitudinal section of the pressure regulating chamber, drawn to an enlarged scale.

Figure 3 is a central longitudinal section upon an enlarged scale of the pumping mechanism shown in Figure 1.

Figure 4 is a central vertical section of another of the regulating devices.

Figure 5 is a transverse vertical section of the pumping mechanism on line 5—5, Figure 3.

Referring more particularly to Figure 1 of the drawings, it will be seen I have illustrated my invention as applied to a household or domestic refrigerator, the same being designated by numeral 10, and drawn schematically. Within the chamber formed by the walls of the refrigerator is a coil 11 through which the refrigerating fluid flows to cool the chamber. Upon the top of the refrigerator is positioned a tank 12 of suitable dimensions to receive a quantity of water, or other suitable fluid, and within this tank is a small coil 13 that is in com-

munication with the refrigerating coil 11 through the interposed pressure regulating element 14. A shut-off cock 15 controls the passage of fluid into the regulating chamber 14 from coils 13, and chamber 14 preferably comprises a cylindrical shell, closed at one end, and having a removable cap 16 at its opposite end. Fitted into member 14 is a cup-shaped element 17 the side walls 60 whereof fit snugly against the interior of chamber 14, and the bottom whereof is provided with an embossment 18 arranged axially thereof and provided with central passage 19. The outer ends of this passage 19 70 are countersunk, as shown, and a spindle 20 of less diameter than passage 19 is positioned in the latter and extends out through cap 16. The inner end of spindle 20 is threaded to receive a conical valve element 75 21 that seats in the adjacent countersunk portion of passage 19, and a similar valve element 22 is positioned upon the spindle 20 upon the opposite side of embossment 18 to seat in the adjacent countersunk portion of 80 passage 19.

A flexible diaphragm 23 of any suitable construction is placed upon the end of cylinder 14 and the side-walls of cup 17 and is secured in position by means of a gasket or ring 23^a that is clamped by screwing down cap 16 upon cylinder 14, as shown in detail in Figure 2. Centrally upon the external portion of cap 16 is a hollow stub 24 that is internally threaded to receive a headed 85 bushing 25, the latter being centrally bored, as at 26, of greater diameter than the diameter of spindle 20 to permit the latter to move freely therein and yet be guided thereby. A wing nut 27 is screwed upon the outer extended end of spindle 20 and a coiled expansion spring 28 is interposed between the inner end of bushing 25 and the adjacent portion of diaphragm 23 and surrounding 90 spindle 20. By adjusting wing nut 27 the relative movement of spindle 20 is limited for controlling valve 21 which may be manipulated without having to open the casing.

The fluid, after passing through chamber 14 into cup 17, passes out of the latter through a hollow stub 29 tapped into cylinder 14 and connected at its lower end to coils 11. After transit through coils 11, the refrigerant passes upwardly into the pipe 105 or extension 30 that extends through the top of the refrigerator to a regulating de-

vice, shown in detail in Figure 4. This structure comprises a cup-like receptacle 31 the lower portion or bottom of which is closed and has a suitable hollow stub 32 into which pipe 30 is screwed, and its upper portion is closed by a cap 33, the annular flange whereof is threaded and screwed down upon the sides of receptacle 31. Within this receptacle 31 is a cup-like structure 34, open at its top, and having a conical shaped bottom 35, the apex whereof is formed into a central embossment 36 having a passageway 37 made axially therethrough, and the ends of which are countersunk in substantially the same manner as passage 19, heretofore described. A spindle 38 extends through this passage 37 and has a conical valve 39 screwed upon its lower end to seat in the lower countersunk portion of passage 37. A similar conical valve 40 is mounted upon the spindle upon the opposite end of stub 36 to fit in the adjacent countersunk portion of passage 37. A diaphragm 41 of any suitable construction is mounted upon the upper end of receptacle 31 and cup 34 and is held in place by a gasket or ring 42 that is clamped down upon the same by screwing on cap 33. Diaphragm 41 is suitably connected to spindle 38, and the actuation of the diaphragm opens or closes the valve upon its ends. Centrally of cap 33 is a hollow stub 43 that is internally threaded to receive a bushing 44 having a central bore 45 of greater diameter than spindle 38 and outside the head of this bushing and preferably bearing against the same is a wing nut 46 that is adjustably mounted upon the threads of spindle 38. The adjusting of this nut regulates the relative movement of the spindle and the seating of the valves with respect to the movement of the diaphragm.

From the structure just described the fluid passes through a short tube 47 to a T 48 having a gauge 49 upon its upper end, and a stub 50 on its lower arm that communicates with the pumping mechanism. Co-ordinated with gauge 49 is a gauge 51 connected by a pipe 52 to a T 53 and the inlet end of coil 13 opposite element 14.

The pumping mechanism to which I have just referred comprises a casing consisting of two cylindrical elements 54 and 55 supported upon suitable standards or feet 56; casing 54 being of shorter length than the other section and the meeting edges of said casing being united by threading and packed by gaskets 57. The casing section 54 has a threaded opening in its outer end into which is screwed a stationary piston element 58 that is reduced adjacent its end to provide a shoulder 59 to seat against a gasket 60 positioned between the same and the end of casing 54, while a nut lock 61 and a gasket 62 are secured to the outer extended end of

the piston element so that the latter is securely fastened in position and the joint is packed to prevent the escape of fluid or other material. Piston element 58 has a bore 63 that is enlarged, at 64, within the casing to receive a headed plug 65 that is screwed thereon and provided with a gasket 66 therebetween. The plug 65 is hollow and has a passageway 67 through its head that is countersunk to receive a valve 68, the stem 69 whereof passes through a closure plate 70 that is threaded on its edge and screwed into the adjacent portion of plug 65. This closure plate 70 has transverse apertures 71 formed therein, and a spring 72 of the expansion type surrounds the spindle of the valve between head 68 and plate 70 to normally retain the valve in seated position.

A reciprocable cylinder 73 surrounds the exterior of the stationary piston element 58, and is guided between the same and the inner surface of casing elements 54 and 55; the casing sections 54 and 55, the stationary piston element 58 and the movable cylinder 90 73 are of such interior and exterior dimensions that there is a snug sliding fit between the same. The closed end of the cylinder is provided with a hollow stub 74 that is threaded upon its exterior to receive a cup-shaped sleeve 75, the outer end whereof is screwed upon the reciprocable shaft 76 that extends out through the opposite end of cylinder casing 55. The latter element is provided with a hollow stub 77 upon its outer end that provides a stuffing box through which rod 76 reciprocates, and is provided with a suitable gasket 78 and a gland nut 79. Stub 74 of the cylinder casing guides the spindle 80 of a conical valve 81 that seats a countersunk opening 82 in the cylinder head, and a spring 83 extends between a shoulder formed in the valve seat and a nut 84 secured upon the opposite end of spindle 80 to retain the valve normally seated.

Passageways 85 are made upon opposite sides through cap 75 and hollow stub 74 so that refrigerating fluid received through pipe 50 that is tapped into casing section 55 will pass into the cylinder past valve 81 upon the movement of the cylinder in one direction to admit the fluid into the interior chamber of the cylinder. When the cylinder is moved in the opposite direction the valve will seat, and the fluid under pressure is forced against valve 68 which opens and permits the fluid to pass through apertures 71 into passageway 64 and out into coil 13 that are connected to the stub end of the stationary piston element.

A suitable cup 86 is secured in casing section 54 adjacent its outer end and below a suitable plug 87 in the upper section of the casing to afford facilities for draining and

cleaning out. An oil feed 88 of any suitable type is mounted upon a convenient portion of casing section 55 and communicates with the interior thereof, and a cup 89 is 5 tapped into the lowermost portion of the casing section 55 adjacent its outer end and controlled by means of a cock 90 mounted in the stub of said cup, in order to drain off such surplus oil as may accumulate in the 10 cylinder.

It will be observed that the pressure developed in the cylinder 73 will operate between the interior walls of the cylinder and stationary piston 58 and between the exterior walls of cylinder 73 and the interior walls of the exterior casing in a direction tending to prevent the flow of such oil as is not carried on these parts by friction and which is necessary for lubrication with cylinder 20 73.

What I claim is:

1. A pump comprising a hollow casing, a stationary plunger mounted in one end thereof and spaced from the walls thereof; 25 said plunger being centrally bored to provide therethrough a discharge outlet for said casing, a valve at the inner end of the bore of said plunger for controlling said passageway, a hollow stub extending from 30 the opposite end of said plunger through an aperture in the adjacent end of said casing, a rod reciprocable in the opposite end of said casing, a movable pump cylinder reciprocable in said casing and open at one 35 end to telescope said plunger, an oil-trap communicating with the lower segment of said casing beyond the path of movement of said pump-cylinder, a valve cage in the

end of said pump cylinder nearest said rod and to which said rod is connected said 40 valve cage having lateral ports that provide an inlet passageway into said pump cylinder, a valve in said cage back of said ports and controlling said passageway, means for admitting fluid into said casing and outside 45 of said cylinder, and means for reciprocating said rod.

2. A pump comprising a hollow casing, a stationary plunger mounted in one end of said casing and extending outside the same, 50 said plunger having a bore providing discharge passageway extended through said casing, a hollow plug screwed into said bore and closing the inner end of said passageway, said plug having a shouldered exterior 55 to abut the end of the plunger, a check-valve in the bore of said plug permitting only the outward flow of fluid through said passageway, a pump cylinder reciprocable within said casing and open at its end to 60 telescope said plunger and plug, a hollow stub extending axially from the end of said cylinder opposite said plunger, a check-valve in said stub permitting only the inward flow of fluid to the interior of said 65 cylinder, said stub having lateral ports communicating with its interior chamber adjacent said valve, and a reciprocable rod connected to said stub for actuating the cylinder; said rod journaled axially in the end 70 of said casing opposite the end in which said plunger is mounted.

Signed at Chicago, county of Cook and State of Illinois.

SOLOMON M. MILLER.
